UNITED STATES PATENT OFFICE

HERBERT K. BAKER, OF DETROIT, MICHIGAN

APPARATUS FOR SLITTING METAL SHEETS

Application filed August 28, 1931. Serial No. 559,945.

This invention relates to apparatus for slitting metal sheets. More particularly, the invention is concerned with reciprocating press mechanism having punches mounted therein and arranged for cooperative slitting of metal sheets or blanks particularly of the type employed in the production of expanded metal lathing.

Generally considered, the present invention has in view increasing speed of production, enhancing the strength and life of various parts employed and, in addition, simplifying the mounting, original fabrication and replacement of the slitting parts.

More specifically, this invention contemplates the use of a plurality or multiplicity of cooperating slitting punches arranged in groups in each of the cooperating press members to interleave upon actuation thereof. It should here be noted that various difficulties and disadvantages have been encountered in machines, utilizing a multiplicity of cooperating punches, which have been heretofore employed. The nature of these disadvantages will be more apparent when it is considered that, in using a multiplicity of slitting punches, the surface contact of the punches themselves with the blanks is very great, producing a relatively heavy impact at each stroke of the press. This heavy impact is not only likely to result in irregularly formed slits and ultimate strands in the meshwork of the material but, still more important, subjects the slitting mechanism, particularly the punches thereof, to very severe strains and shocks. As a result, the slitting punches not infrequently become warped and broken.

This disadvantage has materially held back or hindered the development and use of slitting mechanisms employing large numbers of slitting elements or punches. It is apparent, of course, that it is desirable to employ an apparatus having a large number of slitting punches mounted therein for the reason that this materially enhances speed of production.

The present invention has in view overcoming disadvantages encountered heretofore such as those just referred to above by

the provision of a slitting punch arrangement which lends itself very readily to shaping or tapering of the cutting edges of the punches themselves in such manner as to provide a shearing action in the production of the slits.

To further bring out the character of the novel features here referred to, attention is called to the fact that heretofore in this art, in most instances where it was desired to employ a machine having a multiplicity of slitting punches, the machine included a plurality of groups of slitting elements arranged for cooperative slitting of blanks by relative reciprocation, the slitting elements each being notched or recessed in a cutting edge thereof to provide for interruption of the elongated slit which would otherwise be produced. The plurality of slitting elements of this type heretofore employed were arranged in groups, in the reciprocating press members, to cooperate with each other and produce slits in the blanks at one edge only (the notched edge) of each element. Another arrangement of such slitting punches heretofore adopted is that in which each element was provided with two slitting edges only one of which was notched or recessed and in which the cooperating elements were arranged to interleave so that the notched edges of those in one press member cooperated with the plain edges of those in the other press member, and vice versa.

In both of these prior arrangements it is very difficult if not impossible to machine or shape the cutting edges of the punches so that they will provide a shearing action upon actuation of the press. Indeed, as a practical matter, no attempt was made to provide such shearing action and, in consequence, the prior arrangements resulted in tremendous impacts or shocks to the press in general and to the punches in particular by virtue of the flat and materially extended surface contact of the punch cutting edges with the blanks being slit.

This condition, of course, is most serious where the slitting apparatus includes a series or plurality of punches disposed lengthwise of the feed of the apparatus as well as trans-

versely thereof. The present invention has in view the elimination or, at least, the material reduction of difficulties of this character as will appear more fully as this discussion 5 proceeds.

Another point which should be observed in this connection is the fact that replacement or regrinding of the slitting punches is the major item involved in the upkeep of the 10 apparatus so that, in accomplishing the foregoing projects, the present invention results in material reduction of maintenance or upkeep costs.

With the foregoing in mind the present 15 invention contemplates the use of a multiplicity of slitting punches arranged or mounted in two cooperating press members in position to interleave upon actuation of the members, each slitting element having a pair of slitting 20 edges which are spaced from each other a distance greater than the width of the strands ultimately to be produced. That is, each slitting punch is machined to provide a slitting or cutting edge at each side of a 25 flattened portion of the punch element, this flattened configuration, in the preferred arrangement, also being extended throughout the entire punch, so that each element takes the form of a parallel sided plate member 30 which may readily be fabricated or machined from suitable tool steel sheets. Still further, in accordance with the preferred embodiment, each punch element is of width or thickness substantially equal to twice the 35 width of the strands to be produced, and the spacing between the punches of each group is of similar width to provide for the interleaving of cooperating elements of similar configuration and dimensions.

40 The punches of the present invention are also mounted in the press members so that their cutting edges are slightly inclined or obliquely set with respect to the direction of feed of blanks through the apparatus, the 45 result of this being the production of similarly inclined series of slits in the blanks. With the length of the feed steps, the inclination of the punches, and the width of the punches properly relatively arranged and 50 proportioned, the strands are produced by production of one group of slits (as a result of one press movement) and the subsequent production, by the same sets of punches, of additional slits interleaving with or extended 55 partially between slits produced by the first press movement. The manner in which these operations are effected will be more apparent, of course, from a consideration of the following description of the accompanying 60 drawings.

In any case, with slitting punches arranged and configured as brought out above, the punch elements themselves may much more readily be shaped or rounded off at their cutting edges to provide for a shearing action. 65

In addition to the much more sturdy and long lived construction (resulting from multiple width punch elements), the present invention further contemplates greatly simplifying and facilitating the construction of the punches 70 to provide for a shearing action.

The nature and advantages of this feature will be still more apparent upon consideration of the fact that in accordance with the present invention the slitting punch elements are multiple in character. That is, each slitting punch element is not only of flattened plate-like configuration but also is cut out or recessed at its working edge to provide a plurality of independent and spaced punch portions. With punches of this character arranged to interleave upon actuation of the press members and to form slits at each side thereof, each individual punch portion of said 80 multiple elements may conveniently be tapered off toward the ends of its working or cutting edges to provide for the shearing effect above referred to. As an additional advantage, it should be observed that the punch portions of these multiple elements may very 85 conveniently be machined, at least as to certain faces thereof, together as a unit. The work and time involved in the production or regrinding of the elements, therefore, is reduced to a minimum.

90 Multiple punch elements of the character above described are still further advantageous in materially simplifying the mounting arrangements necessary in securing the various groups thereof in the press members. In this connection it should be borne in mind that where the punches are multiplied lengthwise as well as transversely of the feed of the blanks through the apparatus, the mounting and securing of the various parts and elements is very considerably complicated. With applicant's multiple punch elements, however, the number of individual parts, which must be placed and secured within a 100 certain group of parts in the press, is reduced to a minimum, it being borne in mind that, according to this invention, a single base portion, for a plurality of individual and separated effective punch portions of each element, is all that is necessary for the purpose of obtaining the necessary backing in the press member as well as for the purpose of fastening or securing the part in its proper position.

105 Another feature of this invention which should here be brought out is involved in the use of a novel stripper mechanism for the punches. Before considering the objects and advantages of the particular stripper mechanism here referred to, attention is called to the fact that where multiple slitting is being carried out, particularly where a multiplicity of slitting punches are arranged generally lengthwise as well as transversely of the feed 110 of blanks through the apparatus, very effec- 115

tive or complete stripping action is necessary in view of the fact that the great number of punches employed results in correspondingly increased engagement of the blanks. It has been very difficult heretofore to provide sufficient stripping action for press mechanisms in which the punches were multiplied lengthwise as well as across the feed, especially in the production of narrow stranded meshwork such as that now commonly employed, because of this extended engagement of the punches with the blanks. This difficulty arose by virtue of the fact that it was possible to dispose stripper members in the press to engage the blanks only between separated groups of punches and to the front and rear of such groups of punches. Obviously, such an arrangement, especially where the punches are arranged in multiple lengthwise of the feed, left very large areas, defined by the dimensions of the groups of punches, entirely without adequate stripping action.

However, where punches of multiple thickness or width are employed, the spaces between adjacent punches in each group are of sufficient dimensions to permit the insertion of disposition of stripper ligaments or fingers therein. This, of course, results in very complete or thorough stripping action between the punches themselves as well as in areas surrounding the groups thereof. The present invention, therefore, materially reduces difficulties heretofore encountered in the stripping of the blanks from the slitting punches in a machine in which the punches are multiplied lengthwise as well as transversely of the feed. As a further result, warping of the blanks, sticking thereof on the punches, and also irregularities in feed, are reduced to a minimum.

Another advantage of substantial importance lies in the fact that, in addition to the more accurate feed provided, any inaccuracies which may occur, from time to time, produce only relatively slight variations in the width of the ultimate strands. The reason for this is the fact that where multiple width punches are employed, an inaccuracy in feed is distributed, so to speak, over a plurality of strands, it being borne in mind that the inclined punches cut slits in each operation between those which were produced during a preceding stroke of the press.

The nature of this invention, the objects and advantages referred to above, and also still further advantageous features, will be more apparent from a consideration of the following description making reference to the accompanying drawings, in which

Figure 1 is a bottom face view of the upper of a pair of cooperating press members embodying various features of this invention, the view including certain portions broken away to disclose others lying therebehind;

Figure 2 is a vertical sectional view

through the pair of press members taken substantially as indicated by the section line 2—2 on Figure 1;

Figure 3 is an enlarged view taken similarly to Figure 2 but illustrating certain details of the slitting punch arrangements;

Figure 4 is a view of two groups of slitting punch parts mounted in the lower press member, this view being taken as indicated by the line 4—4 on Figure 3 and showing the punch parts in top plan;

Figure 4a is a view also taken substantially as indicated by the line 4—4 of Figure 3 but showing punch elements, in horizontal section, mounted in the upper press member;

Figures 5 and 6 are side or face views of two punch parts which I prefer to employ in the lower press member;

Figures 7 and 8 are views similar to Figures 5 and 6 but illustrating punch parts which I preferably employ in the upper member; and

Figure 9 is a somewhat diagrammatic illustration of a portion of a blank which has been partially slitted by the apparatus illustrated in Figures 1 to 8 inclusive; this figure also including various markings, hereinafter explained, to show the manner in which various slits are produced at the successive operations of the press.

Before considering the drawings in detail, attention is first called to the fact that the present invention is in the nature of an improvement on the method and apparatus described and claimed in my copending application, Serial No. 356,331, filed April 19th, 1929.

Referring first to Figures 1, 2 and 3, the upper and lower press members are indicated generally by the reference numerals 10 and 11, respectively. The base member 11 is preferably stationarily mounted while the upper member 10 is arranged for vertical reciprocation on the posts 12, guide apertures 13 being provided in the upper member for this purpose.

Both of the press members are somewhat similar as to their general arrangement and as to the provision therein of a large groove extended transversely of the feed through the apparatus for the purpose of receiving and mounting the various cooperating groups of slitting punches. These grooves or recesses are clearly illustrated in Figure 2, and as here seen, each one of them is provided with a pair of cooperating wedge members 14—15 which may suitably be employed as a means of adjusting the height of the punches within their respective press members. A backing plate 16 may also be disposed in each press member at the outer face of the adjusting wedges 14—15.

The punch elements themselves, as most clearly seen in Figure 1, are arranged in two series extended transversely of the feed

through the apparatus, this feed being in the direction indicated by the arrows 17 in Figures 1, 2 and 3. These series of punches, furthermore, are spaced from each other lengthwise of the feed as clearly illustrated in Figures 1 and 2 and, in addition, include groups of punch elements which are spaced apart from each other transversely of the feed. The general arrangement, still further involves a disposition of all the slitting punch elements angularly or inclined with respect to the direction of feed. Finally, as to the general layout, attention is called to the fact that all the punches in each series are inclined in one direction with respect to the feed while those in the other series are inclined in the opposite direction. Various advantages and objects of this punch distribution and disposition will be considered more in detail hereinafter.

Turning now to a description of a single group of slitting punches, particular reference should be made to Figures 3, 4 and 4a. A group of upper punch elements is made up of two different punch parts together with inter-spacing members. The two types of punch elements employed in each upper group are indicated by the reference characters 18 and 19, these parts being shown more or less in detail in Figures 7 and 8.

In the first series of punches to engage the blank in its movement through the apparatus, as above noted, the inclination of the punches is all in one direction, this inclination being obtained by the use of a punch holder or positioning structure 20 (see Fig. 1 illustrating the upper press member). It will be understood, of course, that a similar holder member 21 is employed for the lower press member as clearly indicated in Figures 2 and 3. Since the upper and lower members are substantially the same in essential respects, a description of one of these parts only will be necessary for a complete understanding of this invention. Referring then to Figure 1 in particular and also to Figures 2 and 3, it will be seen that the holder device for the upper press member is provided with two series of apertures or cutout portions 22 and 23, those indicated at 22 being arranged to receive the groups of punches which are inclined in one direction, and those indicated at 23 being arranged in like manner to receive the oppositely inclined punches. This holder, of course, is securely fixed to the body of the press member as by means of bolts 24.

The punch arrangement or grouping in each one of the apertures 22 and 23 is entirely similar except for certain inversions of parts which is necessary in view of the opposite inclination of the punch parts as between those mounted in the apertures 22 and those mounted in the apertures 23. In Figures 3 and 4a I have illustrated the punch grouping which is employed in one of the

apertures 22 and, in making reference to these figures, as well as to Figure 1, it should be noted that each aperture 22 has mounted therein two groups of slitting punches, these groups being spaced from each other by means of wedge devices 25 and 26. The device 25 is preferably mounted substantially fixedly within the aperture 22 while the wedge 26 is of somewhat smaller overall length in order to provide for relative movement thereof with respect to the member 25 and thus produce a tightening or wedging action against the groups of punches which are disposed at opposite sides of the cooperating wedges. An adjusting bolt 27 threaded into the holder 20 and bearing against the large end of the wedge 26 serves to effect this tightening operation. A lock nut 28 may also be employed to prevent loosening of the parts.

As noted above, each one of the upper groups of slitting punches includes a plurality of punch elements 18 (see Fig. 7) and 19 (see Fig. 8). Each punch part 18 has a base portion 29 which is adapted to bear against the backing plate 16 and at its working edge this punch part is divided or split into a plurality of punch portions proper indicated at 30. Furthermore, as clearly indicated by comparison of Figures 3, 4a and 7, these elements 18 are generally of flattened plate-like configuration so that they may readily be cut or machined from tool steel sheets or the like. The other type of punch element (19) which I employ in each upper punch group is quite similar to that illustrated in Figure 7 but, as shown in Figure 8, this part has a base 31 and a lesser number of separated punch portions proper 32. In the particular embodiment herein disclosed each element 18 is provided with three punch portions 30 while each one of the parts 19 has only two, these two being disposed toward one end of the working edge of the punch, the other end being cut away as indicated in Figure 8 at 33. As seen in various of the figures, each one of the punch portions 30 and 32 is provided with tapered off cutting edges 34—34 to provide a shearing action during the actual cutting.

The relative arrangement of the parts 18 and 19 in each punch group will be apparent from inspection of Figures 1 and 4a. Here it will be seen that I have employed a group of two elements 18 arranged side by side and spaced from each other as by means of spacers 35 (see Fig. 1). Each one of these groups further includes a punch element 19 arranged at opposite sides of the adjacent pair of elements 18. The punch parts 19, however, are reversed in position at the opposite sides of each group so that their cutaway portions 33 fall diagonally opposite to each other across the group.

From inspection of Figures 1 and 4a it

will be apparent that each one of the two groups of punches mounted in the apertures 22 of the upper press member are arranged in exactly the manner above outlined, this 5 feature being of importance from the standpoint of assembly as well as in making replacements, for example, after resurfacing or grinding the cutting edges. Spacer parts 35, of course, are also disposed between the 10 adjacent elements 18 and 19 in each group.

As to the groups of punches which are mounted in the holder apertures 23 (see Fig. 1), it is to be observed that the arrangement is quite similar except that the apertures 23 have side walls which are inclined in the opposite direction in order to set the associated punches in a similarly oppositely inclined manner. In view of this opposite inclination, of course, the side punch parts 15 19 of these groups are inverted or reversed with respect to their positions in the groups mounted in apertures 22. That is, in the 20 groups mounted in apertures 23, the elements 19 have their cutaway portions 33 arranged 25 oppositely to the diagonal arrangement thereof in the groups first described (see Fig. 1). These latter groups, however, are similarly secured within the apertures 23 by means of wedge devices 25 and 26 and adjusting 30 bolts 27.

Turning now to the groups of punches mounted in the lower press member 11, it is noted, in the first instance, that the general arrangement of the parts is entirely 35 similar to that described above, including the manner in which the two groups of punches are spaced from each other and secured within the apertures in the holder 21 of the lower press member. A detailed 40 showing of these parts as applied to lower punch groups, therefore, is not included in this disclosure as it is not believed to be necessary for complete understanding of the invention.

45 In Figures 5 and 6 I have illustrated the two types of punch elements which I prefer to employ in the lower groups, these elements being indicated generally by the reference numerals 36 and 37. The parts 36 may be 50 substantially rectangular or square in outside configuration and are arranged with their base portions 38 bearing against the backing plate 16 of the lower press member. The working or cutting edges of the parts 55 need not be interrupted or separated into portions such as those illustrated at 30 and 32 in Figures 7 and 8, but may be left entirely straight throughout the length thereof as indicated at 39 in Figure 5. With respect 60 to the parts 37, it is noted that the working portion or edge is here substantially cut back as indicated at 40 in order to leave only a relatively short cutting edge portion 41. These parts are also arranged with their 65 bases 42 adjacent the backing plate 16.

The arrangement of the parts 36 and 37 is similar to that described above in connection with the parts 18 and 19. In this instance, however, I employ a central group of three punches 36 (see Fig. 4) at each side of which one of the elements 37 is arranged. It will also be seen in Figure 4 that the parts 37 are disposed so that their cutting portions 41 are disposed diagonally across the group in a manner similar to that referred to above 70 in connection with the punch parts 19. Spacing members 43 are also interposed between the lower punches 36 and 37.

Still further, and similarly to the manner described above in connection with the upper 80 punch parts, the two transverse series of lower punch groups are oppositely inclined in order to cooperate with the oppositely inclined upper punch groups. It will also be 85 understood that the arrangement of the elements 37 in the oppositely inclined groups will be reversed or inverted.

Before considering the operation of these various punch parts, reference should be 90 made to Figures 1, 2 and 3 in which I have illustrated a novel type of stripper mechanism applied to the punching elements in order to strip the metal therefrom after each press actuation. This stripper mechanism 95 includes a pair of plates 44 and 45 which are secured to each other at each side of the path of movement of blanks through the apparatus, as by means of bolts 46 clearly illustrated in Figure 1. In addition, the two stripper plates are spaced from each other by means 100 of the strips or parts 47 (see Fig. 2), these parts 47 also being disposed laterally of the intervening groups of punches at each side thereof.

The stripper plates are mounted as a unit 105 on compression springs 48 (see Fig. 2) which may suitably be multiplied along the front and rear edges of the apparatus. In addition, this mechanism is restrained as against upward movement from the press member 11 as by means of brackets 49 having shoulders 50 arranged to engage complementary 110 shoulders 51 on the lower plate member 45.

As clearly seen in Figure 1, each of the stripper plates 44 and 45 is provided with a plurality of elongated apertures 52 of such dimensions as to permit the projection there-through of any one of the punch elements 18, 19, 36 and 37. In this way, stripper fingers 115 or ligaments 53 are disposed in such manner as to fall between the adjacent punches of each group. The stripping action, therefore, is very thorough and complete, this being an important factor in a multiple slitting apparatus of the type herein disclosed for various reasons which are brought out more fully toward the beginning of this specification.

In considering the step by step slitting of a blank by the apparatus herein disclosed, 120 attention is first called to the fact that I pre- 125

fer to employ slitting punches which, in accordance with my copending application above identified, are greater than the width of the strands ultimately to be produced in the blank sheets. Specifically, according to this invention, I employ slitting punches which are twice the width of the strands produced. That is, each cutting portion of each punch has a pair of parallel slitting edges, at its working face, which are spaced from each other a distance substantially equal to twice or double the width of the strands of the meshwork being produced. The strands, therefore, are produced by a double slitting operation, this being accomplished by arranging the punch inclination (with respect to the direction of feed), and the length of the feed step, in such manner that, at one operation, the groups of punches produce slits in the blanks which interleave with or fall between slits produced during a preceding punch operation.

While I have specifically disclosed a punch arrangement in which the punch elements themselves are double the width of the ultimate strands to be produced, it is to be understood that this invention in its broad aspect also contemplates utilizing such multiple width punches of more than twice the width of the strands to be produced. With such modified constructions, however, it will, of course, be necessary to alter the length of the feed step and/or to change the angularity of the punches with respect to the direction of feed so that instead of double or "simple slitting", during successive press actuations, triple, quadruple, or even more finely subdivided slitting will result.

In order to clarify the manner in which the upper and lower cooperating slitting punches actually cut the slits in the blanks, I have, in Figure 4, superimposed the right-hand groups of punches of Figure 4a on the right-hand group of lower elements of this Figure 4. This view clearly brings out which edges of the various double width cutters are effective in the formation of the slits.

In further explanation of the manner in which the slits are produced, attention is now called to Figure 9. This figure illustrates the arrangement of slits which would appear in a blank X which has been fed through the apparatus and subjected to a plurality of punching operations. In this particular instance, the rear edge of the blank is shown at the bottom of Figure 9 at Y, the direction of movement through the press mechanism being again illustrated by the arrow 17. The blank of Figure 9, therefore, may be considered as having been removed from the press mechanism just shortly prior to the completion of the slits therein. For purposes of this description or explanation I have applied a number of brackets to various groups of slits appearing in Figure

9, these brackets arranged in two separate series to designate groups of slits produced by the punches which are inclined in the two opposite directions. Furthermore, the brackets, 1, 2, 3, 4 and 5, are applied to groups of slits in one series while brackets 1a and 2a have been applied to groups of slits in the other or reversely inclined series. It should also be noted that the groups, as defined by the various brackets, are numbered in reverse order with respect to the time at which they are produced by the various punch cutters.

Reference is first made to the series 1, 2, etc., by which it will be seen that in the slitting operation defined by the bracket 1, a plurality of slits s1 are produced. The second bracket is applied to designate the group of slits s2. In a similar manner, the brackets 3, 4 and 5 embrace groups of slits s3, s4 and s5.

The bracketing of the reversely inclined slits, of course, is arranged in a similar manner. In this instance, however, the slits belonging to group 1a are designated at z1, while slits within the group 2a are indicated at z2.

The various groups of slits in the two reversely inclined series, of course, are produced, respectively, by means of the reverse inclined groups of slitting punches. In addition to this, considering one series of slits, it should be noted that the same slitting punches operate on the blank, in the successive press actuations, to produce at each operation one group of slits such as those indicated at s5, s4, s3, etc. The feed step, furthermore, is so arranged that upon the immediately succeeding press actuation a portion of the slits produced overlap or interleave with the first set. Thus the strips of metal which lie between the slits produced in any one given operation are subsequently divided or split centrally by the slits produced in the next following operation.

More specifically, the feed length, this being indicated in Figure 9 by the dimension arrows A, is equal to one-half of the overall extension of any group of slitting punches (lengthwise of the feed) plus a distance equal to the strand interconnecting bridges located between the adjacent ends of any two aligned slits.

With the particular arrangement herein disclosed, i. e., with three slitting punch portions arranged in each group generally lengthwise of the feed through the apparatus (so that a similar number of longitudinally aligned but spaced slits are produced, lengthwise of the feed), the feed step above specified results in the extension of slits produced by any two successive punch actuations, generally speaking, substantially overlapping or interleaving to a point adjacent the mid-points of the two groups.

More specifically, when one group of slits has been produced, the immediately following press actuation results in the production of certain slits which lie completely within the overall dimensions of the first group, other slits which partially overlap or interleave with those produced in the first operation, and still further slits which are extended beyond the area first slitted and lie entirely within an open or unslotted area of the blank. To carry the operation a step further, the slits produced at a third press actuation results in the disposition of certain slits entirely between those last mentioned in considering the second operation. This third operation also produces some slits which interleave only partially with said last mentioned group (making reference to the second feed step), and finally, this third actuation, in like manner to the second, produces still further slits which are disposed entirely beyond the overall dimensions of the complete second group.

If reference be made to Figure 9 which, as noted above, illustrates the condition of a blank just shortly before the slitting thereof has been completed, it will be seen that upon the next feed step (advancement of the blank the distance defined by the dimension arrows A), the punches which produced the slits s_1 (embraced in the bracket 1) will be positioned substantially one-half within this bracketed area and substantially one-half therebeyond in a direction, of course, opposite to that indicated by the feed arrow 17. This will result in "interslitting" between the widely spaced slits s_1 appearing at the bottom of Figure 9.

The manner in which the reversely inclined slits are produced is, of course, identical with that just described, although it should be noted that, in view of the mounting of the reversely inclined punches beyond, with respect to the direction of feed, the punches first considered, such oppositely angled slitting will not begin until several successive operations have been performed by the first mentioned punches. The point at which the second groups of punches begin to operate need not be positioned at any particular point with respect to the operation of the forward cutters, although, as indicated in Figure 9, it is desirable that the slits which are inclined in each direction should be arranged in transverse rows or series throughout the entire width of the blank. In other words, the punches should be arranged in such manner that the slits s_1 , for example, terminate at their ends along the same transverse line on which the slits s_3 terminate. This arrangement, as will readily be understood, may be modified to bring the lowermost slits s_1 into transverse alignment with substantially any of the slits s_2, s_3, s_4, s_5 , etc.

There is, however, one rather important factor to consider in this connection. This relates to the mounting of the various punch groups in the press members. Obviously, if the front and rear transverse sets of punches are arranged very close to each other, mounting difficulties will arise. On the other hand, if the two series are excessively separated, the apparatus is needlessly enlarged and, in addition, inaccurate or irregular feed might result during movement of the blanks between such very widely spaced transverse series.

It is an important feature of this invention, however, as clearly pointed out above, that the punches which are reversely inclined are arranged in series which are spaced substantially from each other thus avoiding serious complications which have been encountered heretofore where punches inclined in both directions have been mounted in a single series extended transversely of the feed. The spacing of the two transverse series of punches is indicated in Figure 9 by the dimension arrows B. An additional advantage of applicant's arrangement should also be noted at this point. Referring again to the type of apparatus in which punches inclined in both directions are included in a single transverse series, it should be noted that even where this has been found to be possible, the resultant slit and strand formation has not been efficient from the standpoint of the total amount of material utilized in producing a meshwork sheet of any given dimensions. Stated in another way, where oppositely inclined punches are mounted side by side transversely of the feed through the apparatus, the punches themselves must of necessity be separated, along the transverse line, more widely than is necessary from the standpoint of obtaining adequate or proper strength and rigidity in the fabric. Thus, according to applicant's invention, the disposition of all the punches which are inclined in one direction in one transverse series, and a similar disposition of the oppositely angled punches in another series spaced from the first, lengthwise of the feed, the oppositely inclined slits and strands may be brought very closely adjacent to each other across the transverse dimension of the sheets.

However, it should be noted that the apparatus of this invention may also be modified to include some punches inclined in both directions in each of the separated transverse series. This might be accomplished, and still obtain at least some of the advantages which I contemplate, by replacing one set of two groups of punches in one series by a similar group, oppositely inclined, taken from the other series. This, it will be apparent, will result in slightly more complicated mounting arrangements and possibly some interference of the punch groups in either or both of

the transverse series but, as noted, will still result in the attainment of advantages herein contemplated at least as to the mounting of certain groups of punches. The foregoing is noted to bring out the fact that while I prefer to incline all of the punches in each transverse series in the same direction, I may also attain objects of this invention by a somewhat modified arrangement. Still other slight modifications may also be made without departing from the general spirit or broad aspect of the invention.

Turning again to the punches of each group, it should also be borne in mind that the essence of the multiple punch arrangement herein disclosed may be incorporated in punch elements which include more or less than three slitting cutters arranged in alignment generally lengthwise of the feed. Obviously, the number may be increased to within any reasonable or practical limit and, with each increase in the number, the detailed arrangement of the punches themselves will be slightly modified and the length of feed of the blanks through the apparatus correspondingly altered.

From the foregoing it will be apparent that high speed production or operation is attainable by the use of apparatus such as that presented as an example herein. At the same time, the structure readily lends itself to the use of the desirably durable double or multiple width slitting punch feature referred to in more detail hereabove.

While I prefer to make the individual punch pieces or elements substantially in the form illustrated in Figures 5 to 8 inclusive, at the same time, a plurality of individual parts may be employed for this purpose. The preferred arrangement, however, affords numerous advantages which are of substantial importance as will readily be understood when it is considered that practically the entire maintenance and upkeep of a machine of this character is involved in replacement and/or regrinding the cutters. The various punch parts lend themselves very readily to tapering or rounding of their cutting edges to provide for a shearing action during actual slitting, this being of very great importance where multiple slitting is being carried out. The term "multiple slitting" as here employed, of course, is used to designate the general type of slitting which involves the formation of a plurality of slits in lines or zones extended lengthwise of the feed, at a single press actuation. However, as will be apparent from comparison of Figures 5 and 6 with Figures 7 and 8, to obtain this shearing action, I need only provide one set of slitting elements (18 and 19) with tapered or rounded cutting edges. This materially simplifies the production and regrinding of the remaining or co-operating slitting parts (36 and 37). Indeed, parts such as 36 and 37 may, even more readily

than parts such as 18 and 19, be machined together in groups, at least as to certain of their surfaces or edges.

Still another advantage of the particular type of slitting punches herein disclosed lies in the fact that only one base portion is employed to support or lend backing to a plurality of more or less independent slitters. This results in accurate alignment of the slitting punches as to their height and, additionally, materially simplifies the mounting and securing arrangements which must be made. In this connection it should be borne in mind that an undue multiplicity of independent or individual parts aggravates the problem of adequate and rigid support. The present invention, therefore, provides a maximum of rigidity and general strength not only inherently in the punches themselves but also in the punches in their individually mounted units or groups.

In considering the mounting and securing difficulties which have been encountered heretofore, and also the manner in which they have been overcome by the structure of the present invention, it should be noted that, in the production of lathing having inclined strands and slits, it is desirable that each row or series of slits transversely of the blanks, and of the direction of feed through the apparatus, should include strands or slits some of which are inclined in one direction and some of which are inclined in the opposite direction. The fundamental reason for this lies in the fact that if all the slits are inclined in one direction, during expansion of the blanks, bending of the strands with respect to their interconnecting bonds or bridges would result in the production of very irregularly shaped sheets and, in addition, would not provide proper strength and rigidity as against bending or flexing particularly on certain diagonal lines.

In order to produce blanks having the desirable oppositely inclined arrangement of slits, in zones or strips extended transversely of the blanks, it is necessary, of course, to dispose slitting punches in groups which are similarly oppositely inclined. In prior constructions such groups of punches have all been mounted within a single elongated zone or area extended transversely of the feed of the blanks through the apparatus. This resulted in considerable complication in suitably mounting and securing the punches in the press members for the reason that, in order to make the best possible or most efficient use of the material being slit, the punches must be disposed closely adjacent to each other within such zone or area so that the slits likewise fall in close proximity to each other. Even where relatively wide unslitted strips or zones were provided in the blanks lengthwise thereof (these zones or strips usually being bent up into strengthen-

ing ribs) it has been difficult to mount the punches sufficiently closely to each other to efficiently make use of the material of the blanks, for the reason that a multiplicity of 5 slits must still be provided between the adjacent unslotted strips. On the other hand, if the number of unslotted strips is increased to further simplify the mounting, this, of course, also resulted in inefficient utilization 10 of the material of the blanks.

In addition to the foregoing, it should be noted that the efficient use of the material and proper mounting of the slitting punches is still more difficult and complicated where 15 a plurality of punches are arranged in the press mechanism generally lengthwise of the feed therethrough as well as transversely of such feed.

With a view to overcoming difficulties of 20 the character above noted, this invention provides for the disposition of the multiple width punch elements above referred to, in two or more zones or areas extended transversely of the feed and preferably spaced 25 from each other lengthwise thereof. Each one of these zones or areas, in accordance with this invention, includes a plurality of slitting punches or slitting punch portions arranged to produce a multiplicity of slits in 30 strips extended lengthwise of the feed as well as transversely thereof. All of the punches of one zone are further inclined in one direction with respect to the feed through the apparatus, while all of the punches of the 35 other zone are oppositely inclined, the punches in each zone being arranged in groups which are spaced from each other transversely of the direction of feed. With 40 such an arrangement, and with the groups of punches in one zone staggered with respect to the groups in the other zone, it will at once be apparent that the construction in general is such as to provide for the production of slits disposed or set closely adjacent to each 45 other transversely of the blanks. This, furthermore, is obtained, in accordance with this invention, without undue complication arising from the mounting of the punches in the 50 press members in view of the greater spacing 55 of the groups of punches.

The mounting is further simplified by virtue of the fact that all of the punches of one group are inclined in one direction, it being noted that where punches inclined in both directions are mounted within a single transverse zone or area, the opposite inclination necessarily brings the punch parts themselves as well as their mounting and securing elements closely adjacent to each other in the 60 direction or in the region of split convergence.

In addition to all the foregoing the use of double width punches in a multiple slitting machine provides the following advantage: 65 In such multiple slitting machines there are,

of course, a great many punch parts engaging the blanks at each operation. Indeed, this engagement is progressively and correspondingly increased as the number of punches is multiplied. In multiple slitting apparatus heretofore employed this extended or increased engagement has resulted in certain "stripping" difficulties, hereinbefore referred to, for the reason that it has not been possible heretofore, at least as a practical matter, to interpose stripping fingers or ligaments in between adjacent punches of any of the groups. This, of course, resulted in relatively large blank areas, defined by the external dimensions of the groups of punches which were left entirely without stripping action. However, according to the multiple arrangement herein disclosed, the use of double width interleaving cutters results in the spacing of the cutters a distance which is sufficient to accommodate stripper ligaments. As will be readily understood, this stripping difficulty has presented itself in its most aggravated form heretofore in multiple slitting machines which were designed to produce some of the more narrow stranded fabrics, these narrow stranded fabrics being more and more widely employed in accordance with modern building practice. While the "stripping" advantage of applicant's apparatus is most advantageous where relatively narrow stranded fabric is being produced, at the same time, the principle of the use of double width punches, in multiple arrangement, with ligaments between adjacent punches, is also advantageous even in producing some of the more widely stranded materials.

A further advantage, over multiple slitting apparatus heretofore employed, is involved in the matter of feed of the blanks. Generally stated, this advantage lies in the fact that a feed inaccuracy of a given percentage will result in a smaller ultimate irregularity in the strands produced than the same percentage of inaccuracy in former machines. This is explained by the fact that the use of double width punches in multiple arrangements results in somewhat extended feed steps which provide for the inter-leaving of slits produced during successive press actuations. A given percentage of inaccuracy, therefore, distributes the irregularity over a greater number of ultimate strands and with this distribution the irregularity as to each strand, of course, is very small indeed. In further explanation of this matter, attention is called to the fact that heretofore where multiple slitting has been adopted, the slits produced at successive press operations did not interleave but were disposed successively entirely beyond previously formed slits. With such an arrangement, where an inaccuracy occurred, the result was an irregular formation

of strands (that is, the formation of abnormally narrow or wide strands) in a single series thereof extended transversely of the feed through the apparatus.

5 In comparing my improved multiple slitting apparatus with others heretofore employed, it should be pointed out that the double width punches arranged in multiple formation, especially when the elements themselves are configured in the manner above described, greatly facilitate the formation of shearing cutting edges. This is due to the fact that the punch portions of each punch element are separated and spaced from each other so that the necessary grinding or finishing may readily be accomplished and, indeed, may be performed on the punches in groups. That is, such shearing edges may be cut or ground on a plurality of punch elements at one operation.

10 The present invention, therefore, provides for the production of much more uniform meshwork than has been possible heretofore, particularly in accordance with the multiple slitting method. Finally, it should be very clear and apparent that a structure such as herein disclosed attains all of the various advantages brought out in the first pages of this specification, as well as those mentioned 15 shortly above, by the use of parts which have maximum strength and life and which, at the same time, are highly desirable from the standpoint of original construction, repair, regrinding, assembly, and the like.

20 35 What I claim is:

1. In combination with cooperating press members adapted to the intermittent feed of blanks therethrough, groups of cooperating slitting punches mounted in the press members and arranged to interleave upon actuation thereof, the slitting punches of each group having their cutting edges inclined with respect to the direction of feed through the apparatus, and there being groups of 40 slitting punches having their punches inclined in opposite directions with respect to the direction of said feed, with the groups inclined in one direction disposed beyond (with respect to the direction of feed) the groups inclined in the other direction.

a device operative as to a plurality of groups of punches for securing them in position.

3. A punch part of generally flattened shape for use in a sheet metal slitting press, the punch part including a plurality of slitting portions also of flattened shape disposed in the general plane of said part and spaced from each other.

4. A punch part of generally flattened shape for use in a sheet metal slitting press, the punch part including a plurality of slitting portions also of flattened shape disposed in the general plane of said part and spaced from each other, each of said portions having a pair of substantially parallel slitting edges.

5. A punch part of generally flattened shape for use in a sheet metal slitting press, the punch part having a working edge portion with a slitting edge at each side thereof, the slitting edges being interrupted or cut away intermediate the ends thereof, and there being an interruption in each slitting edge disposed adjacent to each other at opposite sides of the punch part.

6. A punch part of generally flattened shape for use in a sheet metal slitting press, the punch part having a working edge portion with a slitting edge at each side thereof, the edge portion being cut away or recessed intermediate its ends to provide interruptions in said slitting edges opposite to each other transversely of the punch part.

7. In apparatus of the character described, a pair of groups of slitting parts, each group including slitters spaced from each other, a punch holder member having an aperture therein adapted to receive said pair of groups of slitting parts in spaced relation, and wedge means interposed between the groups of the pair for securing all the slitters of the two groups in their operative positions.

8. In a slitting press mechanism adapted to the intermittent feed of sheets therethrough, a press member having a plurality of spaced groups of slitters mounted therein, the groups being arranged in at least two series extended transversely of the direction of feed and spaced from each other lengthwise of the direction of feed.

9. In a slitting press mechanism adapted to the intermittent feed of sheets therethrough, a press member having a plurality of spaced groups of slitters mounted therein, the groups being arranged in at least two substantially independently mounted series extended transversely of the direction of feed, with the slitters of the groups in one series all inclined in one direction with respect to the direction of feed and with the slitters of the groups in another series all inclined in the opposite direction with respect to the direction of feed.

10. In a slitting press mechanism adapted to the intermittent feed of sheets therethrough, a press member having a plurality of spaced groups of slitters mounted therein, the slitters of the groups inclined in opposite directions with respect to the direction of feed, with the groups inclined in one direction disposed beyond (with respect to the direction of feed) the groups inclined in the other direction, together with

- the groups being arranged in series extended transversely of the direction of feed, with the slitters of the groups in one series all inclined in one direction with respect to the direction of feed and with the slitters of the groups in another series all inclined in the opposite direction with respect to the direction of feed, the groups of the series further being offset with respect to each other longitudinally of the direction of feed and staggered with respect to each other transversely of the direction of feed.
11. In apparatus of the character described, a press mechanism, a plurality of groups of slitting punches mounted in the press mechanism, each one of said groups including a plurality of punches spaced from each other generally lengthwise of the direction of feed and a plurality of punches spaced from each other transversely of said feed to receive similar punch elements therebetween, and all of the punches of each of said groups further being inclined with respect to the direction of feed through the apparatus.
12. In apparatus of the character described, a press mechanism, a plurality of groups of slitting punches mounted in the press mechanism, each one of said groups including at least the following elements all mounted in close association with each other, a plurality of punches spaced from each other generally lengthwise of the direction of feed and a plurality of punches spaced from each other transversely of said feed, and all of the punches of each of said groups further being inclined with respect to the direction of feed through the apparatus; together with means for securing the punches of each group in operative position as a unit.
13. In apparatus of the character described, a press mechanism, a plurality of groups of slitting punches mounted in the press mechanism, each one of said groups including at least the following elements all mounted in close association with each other: a plurality of punches spaced from each other generally lengthwise of the direction of feed and a plurality of punches spaced from each other transversely of said feed, and all of the punches of each of said groups further being inclined with respect to the direction of feed through the apparatus; together with a stripper mechanism having ligaments positioned for effective stripping action within at least some of the spaces between adjacent punches in each group.
14. In apparatus of the character described, a press mechanism, a plurality of groups of slitting punches mounted in the press mechanism, each one of said groups including a plurality of punches spaced from each other generally lengthwise of the direction of feed and a plurality of punches spaced from each other transversely of said feed, and all of the punches of each of said
- groups further being inclined with respect to the direction of feed through the apparatus, there being groups of oppositely inclined punches spaced from each other generally lengthwise of the direction of feed 70 through the apparatus.
15. In apparatus of the character described, a press mechanism, a plurality of groups of slitting punches mounted in the press mechanism, each one of said groups including a plurality of punches spaced from each other generally lengthwise of the direction of feed and a plurality of punches spaced from each other transversely of said feed, and all of the punches of each of said groups further being inclined with respect to the direction of feed through the apparatus, there being groups of oppositely inclined punches spaced and offset from each other generally lengthwise of the direction 75 of feed through the apparatus.
16. In apparatus of the character described, a press mechanism, a plurality of groups of slitting punches mounted in the press mechanism, each one of said groups including a plurality of punches spaced from each other generally lengthwise of the direction of feed and a plurality of punches spaced from each other transversely of said feed, and all of the punches of each of said groups further being inclined with respect to the direction of feed through the apparatus, there being groups of inclined punches spaced and offset from each other generally lengthwise of the direction 80 of feed through the apparatus.
17. In combination with cooperating press members for slitting metal blanks, cooperating slitting punches mounted in the members, and a stripper mechanism for the slitting punches including a pair of stripper parts secured to each other in spaced relation to provide for the feed of blanks therebetween.
18. In combination with cooperating press members for slitting metal blanks, cooperating slitting punches mounted in the members, and a stripper mechanism for the slitting punches including a pair of stripper parts secured to each other in spaced relation to provide for the feed of blanks therebetween, said mechanism being resiliently mounted on one of the press members.
19. In combination with cooperating press members for slitting metal blanks, cooperating slitting punches mounted in the members, and a stripper mechanism for the slitting punches including a pair of stripper parts fixedly mounted with respect to each other in spaced relation to provide for the feed of blanks therebetween.
20. In combination with cooperating press members for slitting metal blanks, cooperating slitting punches mounted in the members, and a stripper mechanism for the slitting punches including a pair of stripper parts

fixedly mounted with respect to each other in spaced relation to provide for the feed of blanks therebetween, together with spring means for resiliently mounting said mechanism on one of the press members.

21. Apparatus for slitting metallic blanks for expansion into meshwork having strands of predetermined width, including reciprocating slitting mechanism adapted to the 10 intermittent or step by step feed of blanks therethrough, slitting elements having cutting edges spaced apart in parallel alignment a distance greater than the predetermined width of a strand, said cutting edges being 15 inclined with respect to the direction of feed through the apparatus, there being slitting elements arranged generally longitudinally in groups of length considerably greater than the length of a feed step, whereby slits 20 formed in a blank by a portion of a group of slitting elements in one operation lie between and in parallel alignment with respect to the cutting edges of other slitting elements in said group, so that, by continued actuations 25 of said slitting mechanism, strands of said predetermined width are produced.

22. In apparatus for slitting metallic blanks for expansion into meshwork having strands of a predetermined width, cooperating 30 press members adapted to the intermittent feed of blanks therethrough, slitting punches mounted in the press members having parallel cutting edges laterally spaced apart a distance greater than the predetermined width of a strand, and further having 35 cutting edges arranged in longitudinal alignment but inclined with respect to the direction of the feed through the apparatus.

23. In apparatus for slitting metallic 40 blanks for expansion into meshwork having strands of a predetermined width, cooperating press members adapted to the intermittent feed of blanks therethrough, groups of slitting punches mounted in the press members having parallel cutting edges laterally spaced apart a distance greater than the predetermined width of a strand, and further 45 having cutting edges arranged in longitudinal alignment but inclined with respect to the direction of feed through the apparatus, the 50

working faces of slitting punches in a group being configured to provide shearing action to the cutting edges upon interleaving thereof with slitting punches of a cooperating group.

24. In apparatus of the character described, an apertured punch holder member, groups of slitting punches mounted in an aperture of said holder member, and a wedging device operative between said groups of slitting punches including a cooperative pair of parts, one having lateral movement and the other longitudinal movement with respect thereto, together with means for tightening said device to securely hold the slitting punches in position.

25. An article of manufacture, a slitting punch for producing meshwork strands of a predetermined width having parallel cutting edges spaced apart a distance greater than the predetermined width of a strand, and having a series of cutting edges arranged in longitudinal alignment, with the working faces of the punch configured to provide a shearing action to said cutting edges.

26. Apparatus of the character described including press members, cooperating sets of slitting punches mounted in the press members and arranged to interleave upon actuation thereof, and stripper plates apertured to pass the punches of a set to provide for engagement with the punches of a cooperating set, the stripper plates for the cooperating sets of slitting punches being securely fastened together but spaced apart to allow the feeding of blanks therebetween, and said plates further being resiliently mounted, together with means for limiting movement of said plates.

27. In a slitting punch stripping device, stripper plates having apertures therein to allow the passage of the slitting punches of a set to engage the punches of a cooperating set, said stripper plates being securely fastened together in spaced relation, together with means for guiding the blanks between said plates.

In testimony whereof I have hereunto signed my name.

HERBERT K. BAKER.
